UNITED STATES PATENT OFFICE.

WILLIAM E. R. RADEMAKER, OF HOBOKEN, NEW JERSEY.

BALL-ROLLING CONTACT FOR RAIN-SIGNALS, &c.

1,172,047.

Specification of Letters Patent. Patented Feb. 15, 1916.

Application filed June 29, 1915. Serial No. 37,053.

To all whom it may concern:

Be it known that I, WILLIAM E. R. RADEMAKER, a citizen of the United States, residing at Hoboken, in the county of Hudson and State of New Jersey, have invented certain new and useful Improvements in Ball-Rolling Contacts for Rain-Signals, &c.; and I do hereby declare the following to be a full, clear, and exact description of the invention, such as will enable others skilled in the art to which it appertains to make and use the same.

The invention relates to a ball rolling contact for rain signals, etc.

15 The object of the present invention is to provide a simple, practical and inexpensive ball rolling contact designed for use in connection with rain signals and various other devices where a circuit closing device is necessary and adapted to afford a dust, rust, water and fire-proof circuit closing means which will be practically indestructible.

20 A further object of the invention is to provide a simple, practical, and efficient rain signal adapted to be operated by an accumulation of a small amount of rain water and capable of sounding an audible alarm or operating a visual signal or the like for indicating presence of rain.

25 30 A further object of the invention is to provide a rain signal of this character which will not be affected by wind so that the occupants of a house will not be needlessly aroused by an accidental operation of the signal.

35 With these and other objects in view the invention consists in the construction and novel combination and arrangement of parts hereinafter fully described, illustrated in 40 the accompanying drawings and pointed out in the claims hereto appended, it being understood that various changes in the form, proportion and minor details of construction may be resorted to without departing 45 from the spirit or sacrificing any of the advantages of the invention.

50 In the drawing Figure 1 is a longitudinal sectional view of a rain signal provided with a ball rolling contact constructed in accordance with this invention, Fig. 2 is a transverse sectional view on the line 2—2 of Fig. 1, Fig. 3 is an enlarged longitudinal sectional view of the circuit closing device,

Fig. 4 is a transverse sectional view of the same.

55

Like numerals of reference designate corresponding parts in all the figures of the drawings.

60 In the accompanying drawing in which is illustrated the preferred embodiment of the invention, 1 designates an oblong casing designed to be constructed of sheet metal or other suitable material and provided with a removable top 2 which is the form of a hopper or funnel. The casing 1 which is designed to be provided with a suitable drain opening, 3 to permit the water to drain off 65 may be mounted exteriorly of a house in any desired position and the top which has a depending marginal flange 4 to fit on the side 70 and end walls of the casing is provided with a central depending spout 5 located above a depressible tiltable member 6 constructed of sheet metal or other suitable material and supported at one end by a spring 7. The 75 inner attached end of the member has a supporting portion 8 which is normally arranged in an inclined position for holding a rolling ball contact 9 out of engagement with an end contact 10 of a circuit closing 80 device. The said strip 6 is provided beyond the supporting portion 8 with side flanges 11 and it has a bend 12 forming a container or receptacle for collecting sufficient rain water to cause the strip 6 to be depressed 85 for tilting the inclined support 8 and a tube or casing 13 in the opposite direction for causing the ball 9 to roll toward the contact 10 to close the circuit for operating an electrically controlled signal not shown. The side 90 flanges of the chute portion of the strip or member 6 is preferably deepened or widened as shown at 14 to provide a receptacle or container portion of the desired capacity to depress the member 6. The member 6 95 will remain in a depressed condition as long as it continues raining and when the rain ceases any small amount of water remaining in the receptacle or container portion 14 will be drawn off by a wick 15 of suitable 100 material having its inner portion arranged within the receptacle or container portion of the chute and extending therefrom and depending from an inclined terminal portion 16 of the member 6. The inclined terminal portion 16 extends downwardly and

95

105

is arranged at an angle to the adjacent portion of the bottom of the receptacle or container of the depressible member.

While the circuit closing device is shown applied to the rain signal it is of course applicable to various devices having a circuit and requiring circuit closing means especially where the latter is exposed or there is danger of fire as in factories and similar places.

The casing 13 which preferably consists of a tube or cylinder having an end wall 17 and constructed of hard rubber, glass, metal or any other material and provided at the other end with a closure plug 18 of hard rubber or any other suitable material. When metal is employed in the construction of the tube or casing 13 it will of course be provided with proper insulating material but where glass or hard rubber is used such insulating material is of course unnecessary. When the tube or casing 13 is constructed of insulating material it is preferably provided at the bottom with longitudinal strips 19 forming conductors and constructed of suitable metal and extending through the end closure and provided with a binding screw 20 for the attaching of one of the wires of the circuit. The contact 10 which is arranged in the path of the ball consists of a head provided with a stem 21 having a binding screw 22 for the attachment of one of the wires of the circuit. The head and the stem are designed to be constructed of suitable conducting material and the stem extends through the closure centrally of the same and when the ball rolls to the contact 10 it electrically engages the same and the strip or conductors 19 and closes the circuit. The head is provided with a concaved face 23 to conform to the configuration of the ball and the wires 24 and 25 are connected with a suitable signal and a suitable source of current supply, not shown.

45 The circuit closing device may be used as a push button and as the parts are adapted to be hermetically sealed there is no danger of fire and the device is water-proof, dust-proof, rust-proof, and may be maintained in proper condition practically indefinitely.

As the contacts are not exposed and will not rust or oxidize a proper operation of the device is assured and the circuit closer is thereby rendered especially advantageous for use in connection with rain signals and similar exposed devices where ordinary circuit closers soon become defective or inoperative.

60 In order to prevent the device from being affected by wind, a wind shield 26 consisting of a supplemental chute is interposed between the spout and the depressible member. The wind shield which may be supported by a bracket 27 or other suitable

means is constructed of sheet metal and it is provided with side flanges or walls preferably formed by concaving the wind shield transversely and the rear end 28 is extended upwardly and the front end 29 downwardly to cause the water passing through the spout to fall into the chute portion of the member 6. A wind shield will prevent any accidental operation of the rain signal through gusts of wind sweeping over the device.

The ball may be constructed of any desired material adapted for conducting a current to close the circuit between the conductors 19 and the contacts 10.

What is claimed is:—

1. A device of the class described including a tiltable casing provided at one end with a relatively fixed contact, spaced conductors extending the entire length of the casing and located at the bottom thereof to form a track, a ball of less diameter than the casing and of greater diameter than the width of the space between the said conductors so as to roll upon the same out of contact with the casing, said ball constituting a movable contact and arranged to roll into and out of engagement with the relatively fixed contact, and means for connecting the wires of a circuit with the fixed contact and the conductors.

2. A device of the class described including a casing having a funnel or hopper and provided with a spout depending therefrom, a depressible member having an inclined chute and located below the spout, said depressible member having a collecting portion located at the lower end of the chute and adapted to be depressed by rainwater and circuit closing means operated by the said member.

3. A device of the class described including a casing having a funnel or hopper and provided with a spout depending therefrom, a depressible member forming a chute and located below the spout, said depressible member having a collecting portion and adapted to be depressed by rainwater and circuit closing means operated by the said member, and a wind shield forming a supplemental chute and interposed between the spout and the said member, said wind shield having side walls and an upwardly extending rear wall and a downwardly turned front portion.

4. A device of the class described including a depressible member consisting of a chute having a bend forming a collecting portion, said member being also provided with a downwardly extending terminal portion located beyond the collecting portion and circuit closing means operated by the said member.

5. A device of the class described including a depressible member consisting of a chute having a bend forming a collecting

portion, said member being also provided with a downwardly extending terminal portion located beyond the collecting portion, a wick extending from the collecting portion over the terminal portion and circuit closing means operated by the said member.

Copies of this patent may be obtained for five cents each, by addressing the "Commissioner of Patents, Washington, D. C."

In testimony whereof I affix my signature in presence of two witnesses.

WILLIAM E. R. RADEMAKER.
